SMOKING PIPE

Jerome Garraffa, Lindenhurst, N.Y., assignor to Winston
Pipe & Tobacco, Inc., a corporation of New York

Filed May 13, 1963, Ser. No. 74,865

Term of patent 14 years

(Cl. D85—8)

FIG. 1 is a side elevational view of a smoking pipe, showing my new design;

FIG. 2 is a side elevational view of the opposite side;

FIG. 3 is a top plan view;

FIG. 4 is a front elevational view;

FIG. 5 is a rear elevational view; and

FIG. 6 is a bottom plan view thereof.

The dominant features of my design reside in the portion shown in full lines.

I claim:

The ornamental design for a smoking pipe, as shown and described.
